ILLUMINATING MEANS FOR MATRIX
REFERENCE CHARACTERS

Ransom H. Turner, Little Neck, N. Y., and Le Roy W. Willis, Stamford, Conn., assignors to Intertype Corporation, Brooklyn, N. Y., a corporation of New York

Application July 6, 1934, Serial No. 734,024
In Germany April 4, 1934

10 Claims. (Cl. 240—2)

The present invention relates to improvements in means for illuminating the reference characters or marks provided on type or type characters bearing matrices or elements used in type setting or matrix line composing machines to enable the compositor to read and check the matter in process of composition and it relates more particularly to illuminating means for the reference characters of type character bearing matrices employed in typographical machines of the class shown and described in U. S. Letters Patent No. 436,532 granted September 16, 1890.

Reference characters for type elements or matrices are ordinarily provided on one edge of such element or matrix and correspond to the type or intaglio type casting character on another edge thereof. Since the invention is primarily applicable to the well known brass matrices such as those commonly used in typographical machines of the class disclosed in the above noted patent, the invention is shown and will be hereinafter described as applied to character bearing elements of such form.

The reference characters are usually provided on the front vertical edges of matrices of the kind referred to and they comprise light punch marks filled with a pigment to give color contrast between it and the adjacent or surrounding areas of the matrix edges, so that the reference characters will be clearly visible and easily readable by the compositor, an artificial light being usually provided above the assembling elevator of the machine to illuminate the matrices therein and thus aid the compositor in reading the reference characters. Both black and white pigments have been employed for filling the punched reference characters in the matrices, and when the punched reference characters were filled with a white pigment, the surface of the matrix surrounding the white filled character has been treated chemically to render such surface black and thereby increase the color contrast and the readability of the reference characters.

Certain disadvantages however have been found to exist incident to the use of matrices having reference characters filled with pigments to contrast with the adjacent or surrounding surfaces of the matrices. For example, the chemically produced black surface surrounding the white filled reference character wears off in a comparatively short time and the white pigment filling the reference character becomes dirty or darkened. This so reduces the degree of contrast that it is necessary frequently to clean and re-treat the reference character bearing edge

of the matrix, which consumes time and is expensive. When black filled reference characters on the natural brass surfaces of the matrices are employed, readability of the reference characters is lost if the matrices are allowed to tarnish. Furthermore, the artificial light, usually an adjustable electric bulb, illuminates the entire surface of the reference character bearing edges of the matrices and also the electro-plated or reflective surfaces of the various rails and ledges which constitute the assembling elevator of the machine, and much of this light is reflected back into the eyes of the operator, resulting in diminished visibility of the reference characters and eye strain, this objection existing whether the reference characters are white on a black adjacent or surrounding surface or are black on the natural brass surfaces of the matrices.

The primary object of the present invention is to provide means for concentrating the light directed to the assembling elevator upon only that portion of the surfaces of the matrices therein as may be necessary to illuminate the reference characters on the matrices. A further object of the invention is to so arrange such light concentrating means that it will direct the maximum amount of light from an adjustable source of light onto the reference characters on the matrices at all times, the light concentrating means being so disposed as to avoid reflection of light into the eyes of the operator from light reflective parts of the assembling elevator or from the surface of the light concentrating means.

In carrying out the invention, it is preferable to mount a light reflector on the assembling elevator in a position to reflect onto the matrices an approximately horizontal beam of light which is only slightly wider than the height of the reference characters on the matrices. The reflector is also preferably provided with a black, darkened or other non-reflective surface which borders a light reflecting strip or area thereof, the light reflecting strip or area being silvered in the manner of a mirror, or chromium or nickel plated and polished or otherwise brightened to afford the desired reflective power, the darkened or non-reflective surrounding surface preventing reflection of light back into the eyes of the operator. The invention further provides means for adjusting the reflector whereby the reflected light beam will be raised and lowered in conformity with different levels at which the matrices may be assembled in the assembling elevator, the reflector being disposed to direct light

from the light source away from rather than toward the operator's eyes.

To these and other ends the invention consists in certain improvements and combinations and arrangements of parts all as will be herein-after more fully described, the features of novelty being pointed out more particularly in the claims at the end of this specification.

In the accompanying drawing:—

10 Fig. 1 is a section taken vertically through the assembling elevator of a typographical machine and showing the source of light for illuminating the matrices assembled therein, the assembling elevator being provided with reference character 15 illuminating means according to the present invention;

15 Fig. 2 is a perspective view, on an enlarged scale, of the upper portion of the assembling elevator as viewed from a level above the matrices 20 therein, showing the manner in which the reference characters of the matrices are illuminated by the illuminating means provided by the present invention;

25 Figs. 3 and 4 are vertical sections through the upper portion of the assembling elevator, showing matrices assembled at different levels therein and the light reflecting means adjusted to conform therewith; and

30 Fig. 5 is a top plan view, partly broken away 30 and in section, of the right hand end of the assembling elevator.

Similar parts are designated by the same reference characters in the different figures.

Referring to the accompanying drawing, 1 represents the assembling elevator of a typographical machine of the class shown generally in the patent hereinbefore referred to, this elevator being adapted to receive type character bearing matrices M and to assemble them in lines therein, in the usual and well known manner, and 2 represents an adjustable electric lamp which is mounted on the frame of the machine above the elevator in a position to illuminate the machine in the vicinity of the assembling elevator. The elevator is provided with the customary means for assembling matrices at different levels therein in order to enable casts to be made from the upper or lower intaglio type casting character 3 and 4 as commonly used on ordinary two letter 45 matrices, the elevator being provided for this purpose with a rail 5 which is slidable transversely in the front wall of the elevator so that the matrices may rest upon it and thus be supported at an upper level as shown in Figure 4 50 when casts are to be made from the lower type forming characters 4, and when the rail 5 is withdrawn forwardly the matrices may rest on the ledge 6 and at the lower level so that casts may be made from the upper type forming characters 3 in the matrices. It will be understood 55 that the intaglio type forming characters 3 and 4 are formed in the rear edges of the matrices, as usual. The rail 5 is retained in the assembling elevator by a bar 7 which overlies it, the rail 5 being suitably fixed in the elevator. The rail 5 is moved forwardly and rearwardly or in a direction transversely of the elevator to bring it into the operative position shown in Figure 4 or to withdraw it from such position as shown in Figure 3 by a pair of arms 8 which are fixed to a shaft 9, the latter being mounted rotatably in bearings 10 on the front of the assembling elevator, the shaft 9 being provided with a handle 11 for operating it. A separate or supplemental rail section 12 is provided at the right hand end

of the rail 5 or at the matrix receiving end of the elevator, this rail section 12 being also slideable transversely into and out of operative position by an arm 13 mounted rotatably on the shaft 9 and having a separate hand lever 14 for operating it. By such an arrangement, when it is desired to assemble all of the matrices at the upper level in the assembling elevator, the rail 5 and supplemental rail section 12 which forms a continuation thereof, are both set in the operative position shown in Figure 4, and when it is desired to assemble matrices at the lower level in the assembling elevator, only the rail section 12 requires withdrawal since this rail section is sufficiently wide to allow the matrices as they enter the assembling elevator, to drop onto the shoulder 6 which is below the under side of the rail 5 a sufficient distance to allow the lower ears on the matrices to pass under the rail 5 as the matrix line is assembled. 15

20 According to the present invention, the top surface of the bar 7 is inclined downwardly and rearwardly toward the matrix passageway in the elevator and a plate 15 is mounted to slide transversely or forwardly and rearwardly on said bar, 25 in undercut grooves 16 at the ends of the bar 7. Means is provided for sliding the plate 15 in said grooves, the means shown in the present instance comprising a shaft 17 mounted rotatably in bearings 18 on the front of the elevator and a pair 30 of levers 19 fixed on the shaft 17 and engaging in slots 20 formed in the plate 15 near its opposite ends, the lever 19 at the right hand end of the shaft 17 having a downwardly projecting arm 21 which engages an open slot or recess 22 in 35 the right hand edge of the rail section 12.

40 The plate 15 constitutes the light reflecting element, and it may be of any suitable character such as a highly polished metal plate electroplated with nickel or chromium, or this plate 45 may be in the form of a mirror. In carrying out the invention, it is preferable to restrict the area of light reflecting surface of this plate 15 which is exposed to light rays from the usual illuminating lamp 2, the top surface of the plate 15 45 being covered for example by paint or other suitable medium which is preferably black or of a non-light reflecting character, so that the upper surface of the plate 15 presents a panel 23 of high light reflecting properties surrounded by a 50 non-deflecting surface or area 24.

55 With such a light reflecting member, it will be seen from Figure 3 for example that light rays 25 emanating from the lamp 2 will be reflected only from the reflective panel 23, so that a concentrated beam of reflected light will be thrown onto the matrices assembled on the ledge or rail 6 in the assembling elevator. If the matrices are assembled at the upper level or on the rail 5, as in Figure 4, the connection of the two-armed lever 19 with the rail section 12 having adjusted the plate 15 by sliding it forwardly into the position shown in this figure, will raise the level of the light beam reflected by the plate 15 to the same extent that the matrices are raised 60 in the elevator. The concentrated beam of light therefore will always be thrown on the reference characters on the matrices, whether the latter are assembled at the upper or lower level in the elevator, it being understood of course that the reference characters of these matrices are always located at the same vertical position on the front edges thereof. 65

70 It will be seen for example from Figure 2 that the concentrated beam of light from the adjust- 75

able reflecting plate 15 restricts the illumination of the front edges of the matrices to only an area slightly greater than the height of the reference characters, while the remaining surfaces 5 of the front edges of the matrices or the areas thereof above and below the reference characters, are distinctly dark, therefore no light is reflected back into the eyes of the operator from the field on the matrices surrounding the reference characters, and no light will be reflected 10 from the adjacent metal surfaces of the elevator to produce a glare in the eyes of the operator. Moreover, the attention of the operator is confined to the area on the matrix line which is 15 highly illuminated by the beam of light of limited extent which is reflected thereon by the restricted reflective surface of the reflector.

We claim as our invention:—

1. In or for a typographical composing machine having an assembler for lines of elements bearing type characters on one edge and reference characters corresponding therewith on another edge thereof, a source of light for illuminating the reference character bearing edges of said elements, light directing means comprising a reflecting surface below the level of the reference characters on said elements and positioned relatively to said elements in the assembler to receive light from said source and reflect a portion of such light in a defined beam and thereby concentrate the illumination from said source only on the reference characters on said elements.

2. In or for a typographical composing machine having an assembler for lines of elements bearing type characters on one edge and reference characters corresponding therewith on another edge thereof, a source of light for illuminating the reference character bearing edges of said elements, and a reflector having a reflecting surface and adjacent non-reflecting surfaces which limit the area of such reflecting surface, said reflector being positioned relatively to said assembler and source of light to direct a beam of light from its light reflecting surface onto the reference characters on said elements and to cause its non-reflecting surfaces to limit the area of said light beam to the reference characters on said elements.

3. In or for a typographical machine having an assembler for lines of type character bearing elements having reference characters on an edge corresponding with the type characters they bear, a source of light, a reflector having a reflecting surface extending longitudinally of a line of the elements in said assembler and positioned relatively to such line of elements and source of light to reflect a beam of light from the latter onto the former, and light concentrating means 55 associated with said reflector for confining the reflected light beam to the reference characters on said elements.

4. In or for a typographical machine having an assembler for lines of type character bearing elements having reference characters on an edge corresponding with the type characters they bear, a source of light, and a reflector having a reflecting surface extending longitudinally of a line of the elements in said assembler and positioned 65 relatively to such line of elements and source of light to reflect a beam of light from the latter onto the reference characters on the elements composing the line, said reflector having non-reflecting surfaces at opposite sides of said reflecting surface to prevent reflection of light from

said source onto the edges of said elements beyond the reference characters thereon.

5. In or for a typographical machine having an assembling elevator having means for assembling therein at different levels character bearing matrices having reference characters on the edges thereof, a source of light for illuminating the reference characters on the matrices, and a reflector positioned relatively to the matrices in the elevator and the source of light to reflect a beam of light from the latter onto the reference characters on the edges of said matrices, the reflector being movable in a direction to reflect the light beam onto the edges of the matrices at different levels to conform with the different levels 15 at which the matrices may be assembled in the elevator.

6. In or for a typographical machine having an assembling elevator having means for assembling therein at differential levels character bearing matrices having reference characters on the edges thereof, a source of light for illuminating the reference characters on the matrices, and a reflector positioned relatively to matrices in the elevator and the source of light to reflect a beam of light from the latter onto the reference characters on the edges of said matrices, the reflector being operatively connected to the means controlling the level of assembly of the matrices in the elevator and movable thereby to 30 reflect the light beam onto the reference characters on the matrices at different levels according to the level of assembly of the matrices in the elevator.

7. In or for a typographical machine embodying an assembling elevator having a rail movable into different positions to control the assembling of characters bearing matrices having reference characters thereon, a source of light for illuminating the reference characters on the matrices, 40 a reflector positioned relatively to a line of matrices in the elevator and the source of light to reflect a beam of light from the latter onto the reference characters on the matrices, the reflector being movable in a direction to direct 45 such light beam onto the reference characters on matrices assembled at different levels in the elevator, and means connecting said rail and reflector for coordinated simultaneous adjustment.

8. In or for a typographical machine embodying an assembling elevator having a rail adjustable forwardly and rearwardly to control the assembling therein at different levels type character bearing matrices having reference characters on their front edges, a source of light for illuminating the reference characters on the matrices in the elevator, a reflector mounted on the front of the elevator in a position inclined downwardly toward the matrix line receiving portion thereof to reflect a beam of light from said source 55 onto the reference characters on matrices in the elevator, the reflector being movable edgewise toward or from the matrix receiving portion of the elevator to reflect the light beam at different levels onto matrices in the elevator, and means connecting said rail and reflector for simultaneous coordinated adjustments.

9. In or for a typographical machine having an assembler which holds side by side in edge-wise assembled relation lines of individual type 70 character bearing elements each having a reference character at the same level on one edge corresponding with the type character they bear respectively on the other edge, a source of light, a reflector having a reflecting surface extending 75

longitudinally below the line of elements in said assembler and positioned relatively to such line of elements and source of light to reflect light from the latter onto the former, and means associated with the reflector for defining the area thereof exposed to the source of light to thereby cause the reflector to direct a defined beam of light toward the reference character edges of the elements and confine the beam of light to the reference characters on the edges of said elements.

10. In or for a typographical machine having an assembler which holds side by side in edgewise assembled relation lines of individual type character bearing elements each having a reference character at the same level on one edge corre-

sponding with the type character they bear respectively on the other edge, a source of light, a reflector having a reflecting surface extending longitudinally below the line of elements in said assembler and positioned relatively to such line of elements and source of light to reflect light from the latter onto the former, and means limiting the area of the reflector exposed to the source of light to cause reflection of a concentrated beam of light toward the line of elements and confining of the area of the reflected beam of light to the illumination of that portion only of the edge of the line of elements occupied by the reference characters.
